UNITED STATES PATENT OFFICE

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY

SEWING MACHINE

Application filed March 27, 1920, Serial No. 369,280. Renewed January 12, 1929.

The present invention relates to sewing machines and more particularly to sewing machines employed in the manufacture of moccasins and other articles made of heavy leather or similar material.

5 In the manufacture of moccasins a single piece of leather is shaped to form the sides and sole of the moccasin and a toe piece is sewed to the sides about the toe portion to 10 form an enclosure for the toe portion of the foot. Also, a piece of leather is generally sewed to the sides about the rear portion to form a covering for the instep and ankle of the foot.

15 In applicant's co-pending application filed of even date herewith Serial Number 369,279, a curved hook needle lock stitch sewing machine is illustrated and described which is particularly adapted to form the seam between the described parts of a moccasin while the parts are held in place on a last with their edges abutting, means being provided in the machine to turn up the edges slightly in advance of the needle to insure that a sufficient 25 amount of stock will be left above the stitches to obtain a strong and tight seam.

In applicant's co-pending application, Serial No. 349,909, filed January 7, 1920, is illustrated and described a method of forming the seam uniting parts of a moccasin which may be practiced by first trimming the edges of the parts even and forming a groove at a predetermined distance from the trimmed edge on the inner or flesh side of the margin 35 of each part. The margins are then placed together with their edges flush and, of course, with the grooves parallel and opposite to each other. The margins are then temporarily secured together near their outer edges by 40 staples of fine wire which enables the parts to be placed upon a last. While the parts are on the last, pressure is applied to the outer sides of the margins to cause the grooves to be transferred from the inside to the outside 45 of the work and the parts are sewed together with a plain lock stitch which passes in at the base of one groove and out at the base of the other, the stitches appearing on the body portion adjacent the grooves and being invisible 50 on the inside of the work. After the comple-

tion of the sewing operation, the work is trimmed away along a line located at the narrowest part of the substance between the grooves, and the portion then projecting beyond the general surface of the body portions is rubbed down to close the edges together to 55 complete the formation of the seam. An object of the present invention is to provide a sewing machine that is particularly adapted to be employed in the practice of this method.

With this and other objects in view, a feature of the present invention contemplates the provision in a sewing machine for uniting marginal portions of parts of an article, of gripping members for engaging opposite 60 sides of said marginal portions, and means for actuating the gripping members to press said marginal portions together and to feed the work. In case the machine is to be employed to form a seam in accordance with the 65 method above described, the grooves in the margins of the parts are preferably transversed from the inside to the outside of the marginal portions by pressure applied to the outside of the marginal portions before the 70 work is presented to the machine, although 75 obviously the gripping members may be employed as the means for accomplishing this result at the same time as they are being actuated to hold and feed the work. In case the 80 outer sides of the marginal portions of the parts are grooved in accordance with said method, the ends of the gripping members are preferably shaped to fit the grooves so as to ensure that the gripping members will 85 hold the work effectively during the feeding operation and during the passage of the needle through the work.

Other features of the present invention consist in certain constructions, arrangement and combinations of parts hereinafter described and claimed, the advantages of which will be obvious to those skilled in the art.

The several features of the present invention will be clearly understood from the following description and accompanying drawings, in which:

Figures 1 and 2 are side and front elevations, respectively, of portions of a curved hook needle lock stitch sewing machine em- 100

bodying the features in their preferred form; Fig. 3 is a left side elevation, partly in section, of the parts illustrated in Fig. 2; Fig. 4 is a sectional plan view taken on the line 4—4 of Fig. 2; and Fig. 5 is a detailed sectional view taken on the line 5—5 of Fig. 1.

The sewing machine, as illustrated in the drawings, has the same general construction and mode of operation, except as hereinafter described, as the machine illustrated and described in the patent to French and Meyer No. 705,063, dated July 22, 1902. This machine is provided with the usual curved hook needle 2, looper 4, take-up 6, shuttle mechanism 8, and loop spreader 10.

The illustrated machine is also provided with a pair of gripping members 12 and 14 which are adapted to cooperate to grip and feed the work, the member 12 being laterally immovable and the member 14 being laterally movable toward and from the member 12, and said members being movable simultaneously in a direction to feed the work. In Figs. 1 and 4 the gripping members are shown in operative engagement with a portion of a moccasin having a side part 16 and a top part 18 mounted on a last 20. The parts are shown united by a partially formed seam constructed in accordance with the method illustrated and described in said application, Serial No. 349,909, the parts having upstanding marginal portions 22 which are temporarily secured together near their outer ends by fasteners 24 and having grooves 26 formed in their outer sides adjacent the line of division of the margins and the body of the parts. The ends of the gripping members 12 and 14 are shaped to closely fit the grooves in the marginal portions of the parts so that when the gripping members engage the margins, the work will be securely held from both vertical and lateral movement and the marginal portions firmly pressed together. To feed the work the gripping members first engage the work, as shown in Fig. 1, and then the gripping members are advanced toward the needle the length of a stitch. After the feeding movement, the gripping members continue to hold the work a sufficient length of time to permit the needle to penetrate the work, the looper to lay the thread in the barb of the needle, and the needle to withdraw from the work, a lock stitch being formed that is invisible on the inside of the work and that extends from a point adjacent the base of one groove to a point adjacent the base of the other groove, as shown in Fig. 3. As the needle leaves the work, the work is released from the gripping members by the gripping member 14 being swung outwardly from the work to the position shown in Fig. 3, whereupon the gripping members are simultaneously retracted, the work being held stationary at this time by the operator. At the end of the retracting

or back feeding of the gripping members, the members are caused to again grip the work to repeat the cycle of operations.

The gripping member 12 comprises an arm that is secured to a bracket 28 by means of a bolt 30, the bolt extending through a vertical slot in the bracket and threaded into an aperture in the arm to provide for vertical adjustment of the member 12. The gripping member 14 comprises an arm that is secured by a bolt 32 to the lower end of a lever 34 pivoted on the forward end of a shaft 36 mounted in a bearing in the bracket 28, the bolt 32 extending through a vertical slot in the gripping member 14 and threaded into an aperture in the lever 34 to provide for vertical adjustment of the gripping member. The lever 34 is actuated to positively move the gripping member 14 into and out of operative engagement with the work at the proper times by means of a bell crank 38 pivoted on a shaft 40 mounted in the machine frame, and having a cam roll 42 mounted on its rear arm that engages a cam groove in a cam disk 44 carried by the main cam shaft 46 of the machine. The connection between the lever 34 and the bell crank 38 comprises a block 48 pivotally mounted on a screw 50 secured to the end of the forward arm of the bell crank, which block extends through a slot 52 in the end of the upper arm of the lever 34.

The illustrated machine has provision of manually operable means for opening the gripping members to permit the insertion and removal of work between them. To this end the portion of the shaft 36 on which the lever 34 is pivotally mounted is made eccentric to the axis of the shaft, and a handle 54 is secured to the rear end of the shaft. With this construction upon swinging the handle 54 upwardly, the shaft 36 will be turned in the direction to cause the eccentric portion of the shaft to swing the lever 34 outwardly about its pivotal connection with the bell crank 38, thereby moving the gripping member 14 in a direction away from the work. Upon releasing the handle 54 the shaft 36 will be returned to its normal position to return the gripping member 14 into engagement with the work, by means of a coiled spring 56 having one end connected to a pin 60 secured to a lug projecting from the hub of the handle 54, and its other end connected to a pin 62 secured to the bracket 28, this movement of the shaft 36 being limited by the engagement of a stop lug 64 on the hub of the handle 54 with a fixed stop 66 on the bracket 28.

To impart the described feeding and retracting movements to the gripping members 12 and 14, the bracket 28, on which the gripping members are mounted as above described, is secured to a horizontal slide 70 mounted to slide in ways formed in a bracket 72 projecting from the machine frame. The

slide 70 is actuated by means of a lever 74 having one end pivoted on the bracket 72 and its other end provided with a cam roll 76 that engages a cam groove in the cam disk 44. The connection between the cam lever 74 and the slide 70 comprises a block 78 centrally pivoted on the cam lever, which block engages a transverse groove 80 formed in the top of the slide 70. In order that the movement of the parts carried by the bracket 28 may be effected during the feeding operation independently of the bell crank 38, the connection between the bell crank and the lever 34 comprising the pivoted block 48, permits the lever 34 to move laterally independently of the bell crank 38.

While the features described herein are well adapted for use in a moccasin sewing machine, it is to be understood that, except as defined in the claims, certain features of the invention are not limited to use in this particular type of sewing machine.

The nature and scope of the present invention having been indicated and a machine embodying the several features of the invention in their preferred form having been specifically described, what is claimed as new is:—

1. A sewing machine for uniting marginal portions of parts of an article having, in combination, stitch forming devices, gripping members adapted to engage the opposite sides of said marginal portions, manually operable means for separating the gripping members comprising a shaft having an eccentric portion on which one of the gripping members is pivotally mounted, and means for turning the shaft, and means for actuating the gripping members to press said marginal portions together and to feed the work.

2. A sewing machine for uniting marginal portions of parts of an article having oppositely disposed grooves formed in the outer sides of the marginal portions, while the portions of said parts adjacent the marginal portions are held substantially flat in the same plane having, in combination, stitch forming devices including a curved hook needle, gripping members engaging the grooves and arranged to hold the work in position for the needle to enter the work below the groove in one part and to emerge from the work below the groove in the other part.

3. A sewing machine for uniting marginal portions of a top part and a side and sole part of a moccasin having oppositely disposed grooves formed on the outer sides of the marginal portions while the parts are on a last having, in combination, stitch forming devices including a curved hook needle, gripping members engaging the grooves and arranged to hold the work in position for the needle to enter the work below the groove in one part and to emerge from the work below the groove in the other part.

4. A sewing machine for uniting marginal portions of parts of an article having oppositely disposed grooves formed in the outer sides of the marginal portions, while the portions of said parts adjacent to the marginal portions are held substantially flat in the same plane, having, in combination stitch forming devices including a curved hook needle, gripping members arranged to engage the grooves and hold the work in position for the needle to enter the work below the groove in one part and to emerge from the work below the groove in the other part, and means for actuating the gripping members to engage the grooves and feed the work.

5. A sewing machine for uniting marginal portions of parts of an article having oppositely disposed grooves formed in the outer sides of the marginal portions, having, in combination, stitch forming devices including a needle, gripping members engaging the grooves and arranged to hold the work in position for the needle to enter the work below the groove in one part and to emerge from the work below the groove in the other part.

6. A sewing machine for uniting marginal portions of a top part and a side and sole part of a moccasin having oppositely disposed grooves formed on the outer sides of the marginal portions while the parts are on a last having, in combination, stitch forming devices including a needle, gripping members engaging the grooves and arranged to hold the work in position for the needle to enter the work below the groove in one part and to emerge from the work below the groove in the other part.
